(57) **CLAIM**

The ornamental design for a sling back chair, as shown and described.

DESCRIPTION

FIG. 1 is a front perspective view of a sling back chair showing my new design;

FIG. 2 is a left side elevational view thereof;

FIG. 3 is a front elevational view thereof; and,

FIG. 4 is a top plan view thereof.

The fragmented cross-hatching shown in FIGS. 1, 3 and 4 is understood to represent fabric and would be continuous throughout the circumscribed area.

The rear of the chair has not been shown and forms no part of the claimed design.
